MAX PUGATSKY AND SAMUEL MANNES, OF NEW YORK, N. Y.

LINING.

1,121,285.

Specification of Letters Patent. Patented Dec. 15, 1914.

Application filed July 1, 1914. Serial No. 848,415.

To all whom it may concern:

Be it known that we, MAX PUGATSKY and SAMUEL MANNES, both citizens of the United States, and residents of the borough of Manhattan, city, county, and State of New York, have invented an Improvement in Linings, of which the following is a specification.

Our invention relates to linings, and more particularly to waistbands or linings for trousers.

In the manufacture of trousers, it is more or less common practice, at the present time, to sew the waistbands in place by hand. This is relatively slow work, and is also more or less expensive, as it materially increases the cost of production, requiring, as it does, the employment of many hands. Oftentimes, this also necessitates putting work outside of the factory, and when this is done the work is generally carried on under unsanitary conditions, due of course to the class of labor employed in this kind of work.

The object of our invention is the provision of a waistband lining so constructed that it may be made and attached to the garment entirely by machine sewing, in order that the cost may be reduced, the output per operator increased, and the work carried on within the factory under direct supervision and sanitary conditions.

We are aware, in some instances, that heretofore waistband linings have been attached to trousers by machine sewing. For example, we are acquainted with the construction in which a strip of lining has been sewed along one edge to a canvas base or lining strip, and at the other edge to the edge of the trousers, the lining being provided with a plait or fold, beneath which the lining and the base have also been sewed to the trousers. In this construction, however, the main or body portion of the lining is free to pull or work up above the top edge of the trousers, and in use, as a matter of fact, it actually does so in a very short time, and consequently another object of our invention is to overcome this difficulty by so constructing the lining that the main portion thereof is fixed permanently within the trousers.

In carrying out our invention, we preferably employ a stiffening strip or base, a face lining secured along one edge thereof, a skirt lining member, and a main lining

member, the said facing strip, skirt and main lining members being secured together and to the stiffening strip or base, the main lining member then turned over and secured at its free edge to the upper edge of the trousers, which are then turned inwardly, the skirt member folded back, and the stiffening member, together with the face lining member, also secured to the trousers by a line of sewing, which is covered by a skirt member after the same has been returned to its normal position, all of which will be hereinafter more particularly described.

In the drawing, Figure 1 is a perspective view illustrating the upper portion of a pair of trousers fitted with our improved waistband lining. Fig. 2 is an enlarged elevation and cross section on line 2, 2, Fig. 1. Fig. 3 is an elevation showing the manner in which, at the sides, the lining may be completed to provide for the distention of the skirt member thereof, and Fig. 4 is a section on line 4, 4, Fig. 3.

Referring to the drawing, it will be seen that in carrying out our invention, we prefer to employ a stiffening strip 10, which, as will be understood, may be made of canvas, buckram, or other similar material commonly employed for similar purposes. Together with this, we also employ a face lining member 11, which is folded over and extends appreciably over one edge of the stiffening strip, a skirt lining member 12, and a main lining member 13. The skirt lining member 12 is preferably looped, that is, folded on itself, and placed against one side of the face lining member 11, then the main lining member 13 is placed against the outer portion of the skirt lining member, and these members, together with the stiffening strip 10, are secured together by a line of sewing 14, or otherwise. The waistband lining is then complete and ready to be attached to the trousers. In doing so, the main lining member 13 is turned over the line of sewing 14, which then becomes invisible, and its free edge is secured to the upper edge of the material 15, of which the trousers are made, by a line of sewing indicated at 16. After this line of sewing has been made, the lining is turned inwardly so that the then outer edge of the stiffening strip lies within the fold made in the trouser material 15. The skirt member 12 is then turned back, and the same, together with the stiffening strip, are secured to the

- trouser material 15 by a line of sewing 16, all of which is clearly indicated in Fig. 2, and by reference thereto, it will be seen that the main lining 13 is fixed in position by the 5 several lines of sewing and cannot possibly pull or work up above the top edge of the trousers, and also that the line of sewing 17 is completely covered by the skirt member 12, so that the same cannot be seen.
- 10 By reference to Fig. 3, it will be seen that in carrying out our invention, the skirt member 12, in suitable positions, so as to come at the sides of the trousers, may be provided with loops or flaps, indicated at 18 15 and 19, so as to provide for the distention of this part of the waistband in the use of the trousers which come over the hips. It will also be understood that the lines of sewing 14 and 17 may be terminated sufficiently 20 far distant from the ends of the waistband as to enable the operator to properly turn in and sew these ends, as indicated at 20, 21, which are the rear ends, to the adjacent portions of the inturned seamed members of the 25 trousers, similar connections being made, as will be understood, at the front of the trousers. Furthermore, it will be understood that the stiffening member 10 may be carried sufficiently far, in the front portion of the 30 trousers, to enable the operator to suitably attach thereto the members of a clasp 22 by placing the same at the edge of the trousers or at a suitable distance inwardly therefrom.
- 35 We claim as our invention:
1. A trouser waist-band lining comprising
- a stiffening member, a face member covering one edge of the stiffening member, a skirt member, and a main lining member, and main lining member being connected to the stiffening member by a line of sewing at which the main lining member is turned over so that its free edge is adapted to be sewed to the upper edge of the trousers while the skirt member is adapted to cover 40 a line of sewing by which the stiffening member and face member are attached to the trousers, so that the said main lining member cannot work up over the edge thereof.
2. In a pair of trousers, and in combination with the waist portion thereof, a lining comprising a stiffening strip, a face lining member covering one edge of the stiffening strip and secured thereto, a skirt lining member also secured to the stiffening strip 45 and face lining member, at one side thereof, and a main lining member secured along one edge to the said stiffening strips, face lining member and skirt lining member, and at its other edge secured by a line of sewing to the 50 edge of the trousers and then turned inwardly while the said stiffening member, and face lining member are secured to the trousers by another line of sewing which is covered by the said skirt lining member 55 when the same is in its normal position.
- Signed by us, this 27th day of June, 1914.
MAX PUGATSKY.
SAMUEL MANNES.
